PRINTING APPARATUS

Walter B. Payne, Rochester, N. Y., assignor to The Todd Company, Inc., Rochester, N. Y., a corporation of New York

Original application January 25, 1934, Serial No. 708,279. Divided and this application January 15, 1937, Serial No. 120,723.

8 Claims. (Cl. 101—332)

The present invention relates to printing apparatus and more particularly to an improved rotary printing mechanism.

One object of the invention is to provide an improved rotary printing drum or cylinder for cooperation with suitable platen and inking means to print various characters, symbols, and designs in a rapid and efficient manner.

A further object of the invention is to provide an improved rotary printing unit including detachable printing forms or sections, and inking-ribbon means for the type or printing characters of the sections, the unit being particularly adapted for signing checks, drafts, certificates, and other value representing instruments in one or more colors as may be desired.

A further object of the invention is to provide an improved printing cylinder for successively applying different characters or symbols upon substantially the same portion of a sheet or in superimposed relation thereon.

A further object of the invention is to provide a rotary printing unit with one or more detachable printing plates in combination with a multi-colored ribbon or ribbons for cooperation with platen means whereby to reproduce the type or various characters on the plates in one or more colors on the sheets to be printed.

A further object of the invention is to provide two or more printing plates having thereon different parts of selected characters or designs affording a complete signature for application to a check or other negotiable instrument, together with means for operating the plates to successively apply the different parts of the signature to the check.

A further object of the invention is to provide an improved form or holder for printing characters, designs, symbols, and the like constructed for ready and convenient application to and removal from a rotary supporting unit.

A further object of the invention is to provide in a printing form or holder of the class described, improved means for guiding an inking ribbon over the printing portion of the holder.

A further object of the invention is to provide an improved printing plate for applying various characters to sheets, with means for engaging and assisting in advancing and guiding the sheet during the printing operations.

To these and other ends the invention resides in certain improvements and combinations of parts, all as will be hereinafter more fully described, the novel features being pointed out in the claims at the end of the specification.

In the drawings:

Fig. 1 is a fragmentary plan view, partly in section illustrating one embodiment of the invention;

Fig. 2 is a transverse sectional elevation substantially on line 2—2 of Fig. 1;

Fig. 3 is a plan view partly in section of one of the printing plates and the holder therefor;

Fig. 4 is a longitudinal section on line 4—4 of Fig. 3;

Fig. 5 is a transverse section on line 5—5 of Fig. 3;

Fig. 6 is a plan view of a printing plate and holder similar to that shown in Fig. 3 in which the plate is provided with different printing characters or markings;

Fig. 7 is a view illustrating a portion of a check to which is shown applied the written portion of the maker's signature, in conjunction with an identifying sign or symbol;

Fig. 8 is a view showing another portion of the maker's signature applied to the check, and

Fig. 9 is a view showing the complete signature applied to the check.

The same reference numerals throughout the several views indicate the same parts.

The present invention embodies generally apparatus for applying various characters to sheets such, for example, as checks and other negotiable paper, this application being a division of my copending application for Printing apparatus, filed January 25, 1934, Serial No. 708,279.

In the preferred embodiment of the invention the characters, marking, or designs to be printed are carried by suitable forms or holders detachably connected with a rotary printing cylinder or unit beneath which the checks or sheets are advanced by suitable feeding means such, for example, as a continuous belt.

The printing cylinder or unit is rotated in a direction opposite to that in which the sheet is advanced by the feeding means and carries a plurality of printing or character holding elements which engage and operate upon the sheet during each revolution of the unit. The character holding elements may or may not be made to operate upon the same portion of the sheet, but where it is desired to superimpose one design or set of characters upon another, this can be readily done with the present device.

In the operations of superimposing one set of characters or one design upon another, the printing or rotating character-holding elements will successively engage substantially the same portion of the sheet, preferably during each rev-

- olution of the unit. In such an operation, the feed belt will move the sheet in one direction, between the platen and the unit and into engagement with suitable stop means. One of the 5 printing elements will then reverse the movement of the sheet and at the same time print thereon. This element will then release the sheet for return to the stop means by the feed belt, after which the next succeeding printing element 10 will engage and reverse the movement of the sheet during which time it will print substantially on that portion thereof upon which the characters were applied by the first mentioned printing element, following which the sheet will 15 again be released and continued through the machine by the feed belt, the stop means by this time having been returned to normal non-obstructing position by means provided for actuating the same, not shown.
- 20 In the present construction the rotary unit is provided with separate detachable printing plates for printing upon a check or other negotiable paper, one of the plates being designed to print a duplex form of validating signature by printing 25 on the check a facsimile of the name signature of the maker and printing in association with said name signature a predetermined symbolic signature, formed by a representation or design of an intricate character difficult to reproduce or forge, whereby to safeguard the name signature. The other plate is designed to print a protective ground portion for said duplex signature, constituting in effect a background for the signature.
- 30 The present construction comprises a base 10 having a casing 11 thereon provided with a hinged cover 12 for enclosing the printing cylinder 13 and the operating parts associated therewith, the cylinder being supported for rotation 35 by a shaft 18 adapted to be driven by any suitable means, such, for example, as that disclosed in my copending application referred to above.
- Disposed beneath the casing is a continuous belt 26 for feeding the sheets into engagement 40 with a stop 26a which serves to position the sheets for engagement by the printing plates on the cylinder.
- 45 A shelf 27 is carried by the base 10 beneath the casing 11 for supporting the pulleys on which the belt is mounted and other parts, not shown.
- 50 The platen roller 29 which may be formed of any suitable material is carried by a stud 30 on a supporting member 31 secured to the base 10 by means of a screw 32 and an adjustable stud 55 33, Fig. 2. The platen supporting member 31 includes oppositely disposed side portions 34 having slots 35 therein in which are disposed the flattened ends of the stud 30 whereby the latter is prevented from rotating.
- 60 The sheet or check to be operated upon by the printing cylinder is shown at 36 and has applied thereto the protective ground 37, the validating design or symbol 38, and the facsimile of the maker's signature 39, as shown in Fig. 9.
- 65 Suitable means, not shown, is provided for guiding the sheets through the machine such, for example, as that shown and described in my copending application Serial No. 708,279.
- 70 The casing 11 is provided with a bottom wall 48 having an opening 49 therein within which the printing cylinder extends, the side walls of the casing being connected by the transverse supporting members 50 and 51, said members having suitable bearings in which the shaft 18 is 75 mounted for rotation. The ends of the members 50 and 51 are provided with reduced portions 53 which are fixed within slots formed in the upper edges of the side walls of the casing, as shown in Fig. 2.
- Secured on the bottom wall of the casing are 5 one or more brackets 54 in which is journaled a rod or shaft 55 provided with an arm 56 having an offset portion 57 at its free end which normally rests on the bottom wall of the casing, as shown in Fig. 2. The arm is provided intermediate its ends with a roller 58. When the check or sheet to be printed is being advanced through the machine by the continuous belt 26 it will pass under the roller, at which time it will lift the arm 56 to rock the shaft 55 on which is fixed 10 means, not shown, for releasing a clutch mechanism for controlling the operation of the printing cylinder, such as that shown and described in my copending application above identified.
- The printing cylinder unit 13 carried by the 20 shaft 18 is mounted between the supporting members 50 and 51 and comprises a pair of circular plates 105 and 106, Figs. 1 and 2, the plates being connected by two sets of cross rods 107. The plate 105 carries the ribbon feeding and reversing mechanism proper, only a portion of which is shown, while plate 105 carries the cylinder stop dog 101 and associated parts and other mechanism relating to the ribbon spool holding means. The printing cylinder, including the plates 105 30 and 106, is secured upon and rotated by the main shaft through the member 110 fixed to the shaft. Referring to Figs. 1 and 2, the member 110 has an extended recessed portion 110a which is securely fastened to the plate 105 by means of a 35 stud 109.
- The cross rods 107 carry the plate holder 111 to which the signature plate 111a is suitably attached and the opposite cross rods 107 carry the plate holder 112 upon which the background plate 112a is mounted. The plate holders 111 and 112 are substantially the same in construction although suitable means, may if desired, be provided so that the plate holders can not be interchangeably disposed on the printing cylinder. Inasmuch as the plate holders 111 and 112 and associated locking means therefor are 40 substantially identical, the same reference characters will suffice for both.
- The printing plates are each provided with an 45 inking ribbon, the ribbons preferably being of different colors, and if desired, one or each of the ribbons may be of the multi-colored type, whereby any attempt to fraudulently reproduce the signature by obtaining a photographic copy of the same is made extremely difficult or practically impossible of accomplishment.
- The printing plates are each provided with an 50 inking ribbon, the ribbons preferably being of different colors, and if desired, one or each of the ribbons may be of the multi-colored type, whereby any attempt to fraudulently reproduce the signature by obtaining a photographic copy of the same is made extremely difficult or practically impossible of accomplishment.
- The plate holders 111 and 112 are each provided with an arcuate portion 113 substantially concentric with the peripheral portions of the 55 plates 105 and 106, to which the printing plates 111a and 112a are attached. The side portions 114 and 115 of the plate holders are extended inwardly from the arcuate portion 113 and are provided with slots 116 at one end each for the 60 reception of one of the cross rods 107. The side portions of the holders are cut away at their opposite ends at 117 to engage the other cross rods 107, the side portions being connected by a rod 118 which is adapted to be engaged by a 65 latch dog 119, pivoted at 120 to a yoke member 121, carried on a cross rod 122, the ends of which are supported by the circular plates 105 and 106. The latch dog 119 is constantly under the tension of a spring 123 connected therewith and 70 75

with the rod 122. Secured to the yoke member 121 is a pin 124 which projects through an elongated opening 125 in the plate 105, as best shown in Fig. 1. The pins 124 extend outside of the circular plate 105 and are accessible for manual operation as a means for releasing the plate holders. In releasing the holders 111 and 112 the yoke members 121 are rocked upon their respective pivot rods 122 by means of the pins 124 in order to withdraw the yielding latch dog 119 from the rod 118. When the yoke member 121 is rocked, the dog 119 yields against the tension of the spring 123 and passes over the rod 118, thereby releasing the plate holder and allowing it to be readily removed from the supporting cross rods 107. When the dog 119 is withdrawn from engagement with the rod 118, the portion 126 thereof engages the portion 127 of the yoke member 121, thereby limiting the inward movement of the dog 119 by the tension of the spring 123.

The inking ribbons 128 and 129 are guided by the holding members 130 for the printing plates in order to assure the proper position of the ribbons with respect to the plates. Referring to Figs. 3 to 6, inclusive, the ribbon guide members 130 are disposed beneath the plate holders 111 and 112 and are held in position by the lugs 131 and rod 118 extending through the lugs. The plates 130 are provided with openings 132 in the center thereof to allow for free operation of the latch dog 119. At the ends of the ribbon guide plates 130, there are provided fingers 133 and 134, which overlie the ribbon to guide and retain it in proper relation with respect to the printing plates.

The rotary printing unit is provided with two independent ribbons and two spools for each ribbon. The feeding and reversing mechanisms for the spools may be of any suitable design, such, for example, as that shown and described in my copending application, Serial No. 708,279. Referring to Figs. 1 and 2, the spools for advancing the ribbons are shown at 135 and 136. Secured to the cylinder plate 105 is a U shaped bracket member 137, one for each ribbon spool. A spring plunger 139 is guided in the member 137 and extends through the plate 105 and the sliding bushing 138 which is rigidly secured to the plunger. The bushing 138 is provided with a collar 140 which limits the movement of the plunger under the pressure of the spring 139a. The plunger 139 is provided with a reduced end 141 inserted within a central opening in the spool. The bushing 138 has secured thereto a disk 142 which is provided with a notch 143. The end flanges of the ribbon spools 135 and 136 are provided with lugs 144 normally disposed within the notches 143 of the disks 142. The plunger 139 extends beyond the extremity of the U shaped member 137 and attached thereto is a knurled operating member 145 for rotating the spool. When it is desired to remove the ribbon spools the plungers 139 are withdrawn against the tension of the springs 139a and at the same time the disks 142 are moved outwardly from engagement with the lugs 144 on the spools.

The printing cylinder plate 106 has secured thereto a bushing 146 corresponding to each spool which carries a rotatable stud 147 provided with a reduced end 149 and having secured thereto a disk 148. The disk 148 is also provided with a notch, not shown, for receiving a lug 150 formed on the adjacent flange of the ribbon spool. The end 149 of the stud 147 also enters

the central opening of the ribbon spool to form a support for the spool. The stud 147 is provided with a toothed wheel 151 adjacent the bushing 146, Fig. 1, the spools being operated by the toothed wheels corresponding thereto and the wheels being driven by any suitable means such, for example, as the automatic spool reversing and driving means embodied in my copending application referred to above.

The printing plate holders 111 and 112 are each provided at one side thereof with a series of parallel grooves and intervening ridges adjacent the printing plates as indicated at 295 in Figs. 1 and 3. These roughened portions 295 serve primarily for assisting in the accurate advancement and feed of the sheets. When more than one printing plate is used as in the case of providing superimposed impressions, the roughened portions 295 of the plates extend the same longitudinal distance on the plates regardless of the length of the subject matter on either of the plates. The facsimile signature or symbol provided on the plate 111a may not in some cases require the entire surface of the plate. Furthermore, there are, under normal circumstances, spaces provided between the parts of a name; such as, between the surname and middle initial, between the initial and given name, and also between the given name and the symbol in the event it is used. Therefore, the portions 295 serve to feed the sheet in an un-interrupted path between the spaced parts of the name and when no printing surface of the plate is in cooperative engagement with the platen.

The printing plates 111a and 112a are provided slightly shorter than the roughened portions 295 of the plate holders 113. This arrangement provides for the portions 295 coming into cooperative engagement with the sheet and platen roller 29 in advance of the printing plates and leaving same slightly after the plates. The portion engaging the sheet slightly ahead of the printing plate causes an initial movement of the platen roller and the sheet so that the sheet is moving when the edge of the printing plate comes in contact therewith. This arrangement eliminates the necessity of the plate starting the movement of the sheet which may cause a smudge or result in an uneven impression. The portions 295 continue to feed the sheet after the ends of the printing plates leave the sheet so as to also eliminate the possibility of a smudge or uneven impression.

With the present method of handling checks the usual data, including the printing of the characters constituting the "amount" is applied to the check prior to the step of affixing the maker's signature. Inasmuch as checks are generally run through a machine to have the "amount" and other data applied thereto just prior to their insertion within the check signer, the ink applied by the first machine may not be thoroughly dry by the time the check reaches the printing plates of the check signer and to avoid transfer of the ink on the check to the printing plate holders the grooves and ridges are provided in the latter to substantially reduce the area of that portion of the holders permitted to engage the check. The ridges of the printing plate holders of the present machine are in a position to contact with the printed "amounts" of the checks at the points at which they are generally applied to the checks.

It has been found that by providing a series of ridges or other relatively fine projections on

- the portions 295 of the printing plates or the holders therefor that no objectionable amount of ink is picked up from the previously printed "amounts" by the ridges or projections during 5 the check signing operations. The ridges or pointed projections may be formed in any desired manner, and also function as a means for advancing or assisting in the advancement of the checks or other sheets and furthermore serve 10 as a means for guiding and maintaining the check in the desired path of movement during the printing operations.

In the operation of the machine it will be understood that the sheet will be advanced between 15 the platen and the printing device by the belt before the first printing plate has had time to contact with the sheet, this being done substantially at or slightly after the time at which the sheet is arrested by the stop means 26a. As 20 soon as the inking ribbon and the roughened portion 295 of the first printing plate contacts the sheet, the direction of movement of the latter will be reversed by the same, by reason of the fact that the printing device is rotated in a 25 direction opposite to that in which the sheet is moved by the feeding belt. Upon completion of the movement of the sheet by the first printing plate and the resulting printing operation, the feed belt will again advance the sheet into engagement with the stop means which is done before 30 the second printing plate has had time to engage the sheet and reverse its movement.

At this point it may be stated that with the present printing device the second printing plate 35 is so positioned relative to the first and the speed of the operating parts so timed that the second plate will engage and operate upon substantially the same portion of the sheet which was previously operated upon by the first printing plate, 40 thereby superimposing the printed characters of the second plate upon those printed by the first plate as, for example, superimposing the parts 38 and 39 of the maker's signature shown in Fig. 7 on the protective ground portion 37 shown in Fig. 8, the result being the application of the 45 complete signature to the check as shown in Fig. 9.

However, if desired the two printing plates or the characters thereon can be so positioned upon 50 the rotary printing unit and the speed of the parts so regulated as to cause the characters to be applied to different portions of the sheet as, for example, one in advance of another.

It will be understood that as soon as the second 55 printing plate of the present design has completed its printing operation, it will release the sheet which will then be picked up by the continuously rotating belt and carried to its destination, the stop means having in the meantime been 60 moved out of the path of the sheet by suitable automatic operating means therefor, such for example as that shown and described in my co-pending application referred to above.

It will be further understood that in signing 65 the check by applying the complete signature thereto, as shown in Fig. 9, that the ground portion 37 and the symbolical signature portion 38 may be applied at one operation and the name signature 39 at another operation if desired, and 70 that the colors of said portions may be varied to provide for any preferred color combination, as for example by the use of inking ribbons of different colors, or of multi-colored ribbons, as previously stated.

75 It will be also understood that either of the

signature portions 37 or 38 may be omitted if it is preferred to have only one relatively complicated design or symbol associated with the name signature to form the complete signature of the maker of the check. Furthermore, if desired, one or more printing plates may be used in the present machine to apply any desired data to a sheet, without effecting any change in the design of the machine or in its method of operation.

I claim:

1. A printing device for use on a rotary operating element to advance and print on a sheet, comprising an arcuate holder having characters thereon adapted for cooperation with an inking ribbon to print data upon the sheet during operation of said element, and a plurality of spaced parts on the holder at each side thereof and each extending in the direction of the opposite side of the holder and terminating short thereof and beneath which the ribbon is adapted to operate and by which parts it is held in proper relation with respect to the characters during rotation of said element.

2. A printing device for use on a rotary operating element to print on a sheet, comprising an arcuate printing plate having characters thereon adapted for cooperation with an inking ribbon to print data upon the sheet, said plate having one or more angularly disposed portions formed to receive supporting means for the plate on said element, a part connected with the plate for receiving a securing member carried by the rotary element, and a member on the plate at each side edge thereof and extending inwardly of said edge and terminating short of the opposite side edge of the plate, each of said members being adapted to overlie a portion of one face of the inking ribbon and to form guide means for the latter.

3. As an article of manufacture, an arcuate printing section for connection with and operation by a rotary support and for cooperation with a platen and an inking ribbon, said arcuate section having a retaining part for the reception of means on the support for securing the section thereon, and a pair of guides at each end of the section for guiding the inking ribbon over the printing portion of the section, the guides of each pair extending in opposite directions and being spaced one from another and adapted to overlie a portion of the outer face of the ribbon.

4. As an article of manufacture, an arcuate printing section for connection with and operation by a rotary support and for cooperation with a platen and an inking ribbon, said arcuate section having a retaining part for the reception of means on the support for securing the section thereon, and a member disposed on the inner face of the arcuate section and having spaced guides at each of its ends for overlying the outer face of the ribbon and for guiding the ribbon during advancement thereof over the printing portion of the section and permitting the ribbon to be withdrawn from the section by moving it laterally thereof.

5. As an article of manufacture, an arcuate printing section for connection with and operation by a rotary support and for cooperation with a platen and an inking ribbon, said arcuate section having a retaining part for the reception of means on the support for securing it thereon, a plate disposed on the inner face of the arcuate section and having a pair of spaced guides at each of its ends for overlying and guiding the ribbon during advancement thereof over the printing portion of the arcuate section, and means

on said plate engaging the retaining part of the section by which the plate is secured upon the section.

6. As an article of manufacture, a unitary printing section for use on a rotary support, comprising an arcuate printing plate having printing characters thereon and having inwardly extending flange-like portions adjacent its sides formed for the reception of portions of the rotary support, and a part on the printing section for the reception of retaining means on the support, said part extending transversely of the section and having its ends connected with said flange-like portions.

15 7. In printing apparatus, a rotary support, and a printing device on the support comprising an arcuate holder provided with printing characters, said holder having means for guiding an inking

ribbon over said printing characters including spaced parts extending in opposite directions and adapted to overlie portions of the outer face of the ribbon during the printing operations.

8. In printing apparatus, a rotary support, a device for printing on a sheet mounted on and rotatable with the support and comprising an arcuate holder provided with printing characters, said holder having means for guiding an inking ribbon over said printing characters including parts spaced one from another and adapted to overlie the side edges of the ribbon during the printing operations, said holder also having a part for engaging the sheet during the printing operations to assist in guiding and advancing the sheet, and means for securing the arcuate holder on the rotary support.

WALTER B. PAYNE.
